UNITED STATES PATENT OFFICE.

ROBERT E. POWER, OF LOS ANGELES, CALIFORNIA.

DESIGN FOR A LIP-STICK HOLDER.

Application filed June 27, 1925. Serial No. 13,923. Term of patent 14 years.

To all whom it may concern:

Be it known that I, ROBERT E. POWER, a citizen of the United States, residing at Los Angeles, county of Los Angeles, and State of California, have invented a new, original, and ornamental Design for Lip-Stick Holders, of which the following is a specification, reference being had to the accompanying drawing, forming part thereof, which illustrates my new design.

I claim:

The ornamental design for a lip stick holder, as shown.

ROBERT E. POWER.
